United States Patent Office.

J. B. JACKSON AND M. R. JACKSON, OF ROCHESTER, IOWA.

Letters Patent No. 70,854, dated November 12, 1867.

MACHINE FOR SHRINKING TIRE.

The Schedule referred to in these Letters Patent and making part of the same.

TO ALL WHOM IT MAY CONCERN:

Be it known that we, J. B. JACKSON and M. R. JACKSON, of Rochester, in the county of Cedar, and State of Iowa, have invented a new and improved Machine for Shrinking Tires, &c.; and we do hereby declare that the following is a full, clear, and exact description of the same, reference being had to the annexed drawings, making part of this specification, in which—

Figure 1 is a side elevation.

Figure 2 is a section of a grieve-key.

Figure 3 is a perspective view of a grieve.

Figure 4 is a plan.

The same letters are employed in all the figures in the indication of identical parts.

A is a bench, to the top of which the machine is fastened. B is the bed-plate of the machine, formed as represented. C is a stationary jaw, fastened to the bed-piece by bolts, and D is a movable jaw, sliding longitudinally upon the bed-piece, between flanged guides on the side thereof. The sliding jaw D is actuated by the screw F, which passes through the vertical portion of the bed-plate B' and a stirrup, E, bolted to the movable jaw D. By turning this screw by means of a winch, or in any other convenient manner, the jaw D is moved towards or from the stationary jaw C, as desired. X represents a section of a tire, which rests upon the curved upper faces of the jaws C and D. For the purpose of affording a continuous bearing for the tire, the jaw D is constructed with a tongue, D', which fits into a socket, C¹, in the opposite end of the jaw C. C² and D² are vertical sockets in the jaws respectively, to receive the stem of the gripes G, which hold the upper face of the tire, under the edges G¹. A horizontal slot is formed through the jaws at C³, and a corresponding slot through the stem of the gripes at G², to receive the wedge-formed key H, which, being driven therein, draws down the grieve at G¹ upon the tire with a force sufficient to hold it. The grieve rests upon a spring, I, which is placed at the base of the socket C² or D², which press the gripes upwards when the key is retracted, and prevent its escape. The tire, being properly heated, and secured to the jaws by means of the gripes, may be shrunk by the action of the screw F, as may be required.

What we claim as our invention, and desire to secure by Letters Patent, is—

The stationary jaw C, and movable jaw D, in combination with the screw F, gripes G, and keys H, constructed and arranged to operate substantially as and for the purpose set forth.

In testimony whereof we have signed our names to this specification in the presence of two subscribing witnesses.

J. B. JACKSON,
M. R. JACKSON.
